UNITED STATES PATENT OFFICE.

MATH NEUMANN, OF ST. CLOUD, MINNESOTA.

AUTOMATIC CALF FEEDER.

1,417,554.

Specification of Letters Patent. Patented May 30, 1922.

Application filed August 6, 1920. Serial No. 401,721.

To all whom it may concern:

Be it known that I, MATH NEUMANN, a citizen of the United States, residing at St. Cloud, in the county of Stearns and State 5 of Minnesota, have invented certain new and useful Improvements in Automatic Calf Feeders; and I do hereby declare the following to be a full, clear, and exact description of the invention, such as will enable others skilled in the art to which it 10 pertains to make and use the same.

My present invention relates to automatic calf feeders of the type disclosed and broadly claimed in my two United States 15 Patents, #1,276,946, issued August 27, 1918, and #1,325,035, issued December 6, 1919.

To the above end, the invention consists of the novel devices and combinations of devices hereinafter described and defined in 20 the claims.

In the accompanying drawings, which illustrate the invention, like characters indicate like parts throughout the several views.

Referring to the drawings:

25 Fig. 1 is a front elevation of the improved calf feeder;

Fig. 2 is a plan view of the same;

Fig. 3 is an end elevation;

30 Fig. 4 is a plan view of the supplemental frame and pail holders;

Fig. 5 is a front elevation of the same;

Fig. 6 is a fragmentary rear elevation of the supplemental frame; and

35 Fig. 7 is a view in vertical section taken on the line 7—7 of Fig. 4, on an enlarged scale.

The frame of the improved calf feeding apparatus includes four corner posts 8 connected by rails 9, each of said posts comprising a pair of laterally spaced members. Upper and lower rails 10 and 11 are carried by the posts 8 and constitute a part of the frame. The rails 10 are rearwardly inclined, and mounted thereon is a pair of wheel- 40 equipped travellers 12, while the lower rails 11 are horizontal and have thereon a pair of sliding travellers 13. These travellers 12 and 13 are connected on each side of the frame, for simultaneous travelling move- 45 ment on the respective rails, by endless sprocket chains 14, in which said travellers are interposed. Both chains 14 are driven from an upper shaft 15 journaled in the rear post 8 above the upper rails 10, and have 50 secured thereto, between the members of said posts, sprocket wheels 16, over which said

chains run. The sprocket chains 14 also run over front and rear idle rollers 17 and 18 journaled to and between the posts 8. As shown, the shaft 15 is operated by a hand 60 crank 19 and held, with the travellers 12 and 13, in different positions by pairs of ratchet wheels 20, on the shaft 15, and co-operating lock dogs 21 pivoted to the rear posts 8. Rigidly secured to the inner faces 65 of the travellers 12 and 13 are notched disks 22 and 23, respectively.

Carried by the travellers 12 is a rectangular supplemental frame 24 having at its ends trunnions 25 journaled in said travellers 12 and the disks 22. A pair of horizontally disposed U-shaped secondary scale beams 26 have their arms intermediately fulcrumed to the front and rear members of the supplemental frame 24. Skeleton pail holders 27 are pivotally secured to the free ends of the arms of the secondary scale beams 26 for swinging movement. Circumferentially spaced stop fingers 28, on the pail holders 27, are arranged to engage the supplemental 80 frame 24 to limit the downward movement of said pail holders and support the same against swinging movement on the secondary scale beams 26. Pails 29 are removably held in the pail holders 27. The transverse 85 portions of the secondary scale beams 26 are turned toward each other, and underlying the same is a pair of graduated primary scale beams 30 fulcrumed to brackets 31 on the front member of the supplemental frame 90 24. Links 32 intermediately connect the primary scale beams to the transverse portions of the secondary scale beams 26. A shift- 95 able poise 33 is mounted on each primary scale beam 30.

Sliding latches 34 are mounted in keepers on the supplemental frame 24 for co-operation with the notched disks 22 to hold said supplemental frame in different oscillated positions. These latches 34 are simultaneously operated by fingers 35 that are flexibly interlocked therewith and carried by a rock shaft 36 journaled in bearings on the supplemental frame 24 and provided with a hand piece 37, by which said rock shaft may be operated. The free ends of the primary scale beams 30 work in slotted guides 38, secured to the back member of the supplemental frame 24, and are held with the pail holders 27 in their lowermost position by 100 gravity-actuated lock plates 39, pivoted at their upper ends to the guides 38, and hav- 110

ing apertures to receive said free ends of the primary scale beams. To simultaneously operate the lock plates 39 to release the primary scale beams 30, the same are provided 5 with upwardly projecting fingers 40, which extend through offset loops 41 in a rock shaft 42 journaled in bearings on the supplemental frame 24. The rock shaft 42 is provided with a hand crank 43 for operating the same.

To hold the rock shaft 42 in different set positions, the crank 43 thereof is arranged for co-operation, under spring action, with a notched lock plate 44 secured to the supplemental frame 24.

A milk-holding trough 45 is carried by the supplemental frame 24, at the back thereof, and provided at its bottom with discharge spouts 46 arranged to deliver milk 20 from said trough into the pails 29. Normally, the spouts 46 are closed by valves 47 having yoke-like stems 48, the arms of which are mounted in guides 49, on the trough 45, and arranged to be engaged by trips 50 formed by extending the rear arms of the secondary scale beams 26. In the bottom of the trough 45 is a normally closed drain 51, under which is located a discharge spout 52 secured to said trough.

30 A feed trough 53, for meal or other dry food, is carried by the travellers 13 and provided at its ends with trunnions 54 journaled in the notched disks 23 and travellers 13. This trough 53 is held in different oscillated positions by means of a sliding latch 55 mounted in keepers on the travellers 13 for co-operation with the notched disks 23. These latches 55 are simultaneously operated by fingers 56, which are flexibly interlocked therewith, and carried by a rock shaft 57 journaled in bearings on said travellers 13. The rock shaft 57 is provided with a hand piece 58, by which it may be operated.

45

Operation.

The operation of the above described invention may be briefly described as follows:

Before feeding takes place, the pails 29 are out of the pail holders 27, and the supplemental frame 24 and trough 53 are in inverted positions. The operator first turns the supplemental frame into a position to bring the pail holders into an upright position. The pails 29 are then placed therein 50 and the poises 33 shifted on the primary scale beams 30 to weigh the desired amount of milk in the pails 29. The poises 33, of course, normally hold the pails 29 in their raised positions with the trips 50 holding the valves 47 open. If the supplemental frame 24 is not in its uppermost position, the attendant may operate the crank 19 to so position said frame and thereby carry the pails 29 out of reach of the calves, while said 55 pails are being filled. The attendant may

then pour milk into the trough 45 and part thereof will flow through the open spouts 46 and into the pails 29.

Under the increasing load of milk in the pails 29, the action of the poises 33 is overcome and the primary scale beams 30 raised. During the raising movement of the primary scale beams 30, the free ends thereof cam the lock plates 39 outward until they come into registration with the apertures in said lock 75 plates. Said lock plates 39 are then free to swing, under the action of gravity, into positions to cause the free ends of the primary scale beams 30 to enter the apertures therein and thereby automatically lock the 80 said scale beams against return movement.

The purpose of thus locking the primary scale beams 30 is to prevent the pails 29 from rising as the weight of the milk is decreased by the calves drinking from said pails, and thereby cause the trips 50 to again open the valves 47 and allow an additional supply of milk to flow into said pails. After the pails 29 are filled with the milk and further supply thereto cut off by the valves 47, the attendant 90 may operate the crank 19 to lower the supplemental frame 24 and thereby bring the pails within reach of the calves. This lowering movement of the supplemental frame 24 will, of course, impart a rearward traveling movement to the trough 53, so that it is out of the way. When the pails 29 are in their lowermost positions, the weight thereof comes directly on the supplemental frame 24, through the fingers 28, and thereby affords a firm support for the pails while the calves are drinking.

In case it is desired to fill only one pail, one of the valves 47 may be kept closed by lifting the respective primary scale beam 105 30 and securing the same in a raised position by allowing its lock plate 39 to drop into interlocking engagement therewith. While only two pails are shown, it is, of course, understood that the apparatus may be of 110 such size as to hold any desired number of pails.

Meal or other dry food to be fed to the calves, may be placed in the trough 53 and the crank 19 operated to cause the travellers 12 to move rearward, thereby lifting the pails 29 out of the way and causing the travellers 13 to move forward and position the trough at the front of the apparatus.

When the calf feeder is not in use, the 120 pails 29 may be removed from their holders 27 and the troughs 45 and 53 turned upside down into emptying positions by first releasing the latches 34 and 55 from the respective notched disks 22 and 23 and then interlocking the same therewith to hold said troughs in their emptying positions. When the troughs 45 and 53 are in their emptying positions, they may be easily cleaned and left in this position until the next feeding time, 130

thus preventing dirt from settling therein. Any milk remaining in the trough 45 may be removed therefrom, before said trough is turned into an emptying position, by opening the drain 51 to permit the milk to run into the spout 52, where it may be caught in a pail or other receptacle.

What I claim is:

1. In an apparatus of the kind described, the combination with a frame having two sets of track rails, of two sets of travellers mounted on the track rails, means for simultaneously moving the two sets of travellers in reverse directions, a supplemental frame 15 carried by one set of the travellers and a trough carried by the other set thereof, and pail holders carried by the supplemental frame.
2. In an apparatus of the kind described, 20 the combination with a frame having two sets of track rails, of two sets of travellers mounted on the track rails, means for simultaneously moving the two sets of travellers in reverse directions, a supplemental frame 25 carried by one set of the travellers and a trough carried by the other set thereof, pail holders carried by the supplemental frame, and means for locking the travellers in different adjustments.
3. In an apparatus of the kind described, 30 the combination with a frame having two sets of track rails, of two sets of travellers mounted on the track rails, means for simultaneously moving the two sets of travellers in reverse directions, a supplemental frame 35 and a trough carried by one set of the travellers and a second trough carried by the other set thereof, pails carried by the supplemental frame, said first noted trough being provided with spouts arranged to discharge into the pails, normally open valves under strain to close the spouts, and automatic means for opening the valves and then releasing the same.
4. In an apparatus of the kind described, 45 the combination with a frame having upper and lower pairs of track rails, said upper rails being inclined, upper and lower travellers mounted on the track rails, cables connecting the travellers for movements in reverse directions, means for operating the cables, a supplemental frame carried by the upper travellers, pails carried by the supplemental frame, a trough carried by the lower travellers, means for holding the cables with the travellers in different adjustments, said supplemental frame and trough being mounted for movement from filling to emptying positions, and means for holding 50 the supplemental frame and trough in filling positions.
5. In an apparatus of the kind described,

the combination with a frame, of a secondary scale beam fulcrumed to the frame, a swinging pail holder carried by the secondary scale beam, a pail in the pail holder, means for supporting the pail holder from the frame in a certain position thereof to hold the same against swinging movement, a primary scale beam fulcrumed to the frame and connected to the secondary beam, a shiftable poise on the primary scale beam, a trough having a spout arranged to discharge into the pail, a normally open valve under strain to close the spout, and a trip 75 on the secondary scale beam for opening the valve during the upward movement of the pail holder.

6. In an apparatus of the kind described, the combination with a frame, of a secondary scale beam fulcrumed to the frame, a swinging pail holder carried by the secondary scale beam, a pail in the pail holder, means for supporting the pail holder from the frame in a certain position thereof to hold the same against swinging movement, a primary scale beam fulcrumed to the frame and connected to the secondary beam, a shiftable poise on the primary scale beam, a trough having a spout arranged to discharge into the pail, a normally open valve under strain to close the spout, a trip on the secondary scale beam for opening the valve during the upward movement of the pail holder, and a latch plate arranged to 90 automatically engage the primary scale beam and hold the same in a raised position to prevent return movement of the pail holder.

7. An apparatus of the kind described 100 having in combination two sets of superposed supports, the upper of which is inclined, two sets of travelers mounted for movement on said supports, animal feeding devices carried by said travelers, and a common means for simultaneously moving said travelers on said supports, one of said travelers moving forwardly and the other upwardly and rearwardly.

8. The structure set forth in claim 7, and 110 means for locking said travelers in various positions on said supports.

9. The structure set forth in claim 7, said feeding devices being mounted for pivotal movement on horizontal axes, and means 115 for holding the same in various positions of adjustment about said axes.

In testimony whereof I affix my signature in presence of two witnesses.

MATH NEUMANN.
